HEDDLE BAR SECURING DEVICE

Howard O. Coddington, Spartanburg, S. C., assignor to The Andrews Company, Spartanburg, S. C.

Application March 27, 1933, Serial No. 663,062

8 Claims. (Cl. 139—92)

This invention relates to heddle frames, and more particularly to means for securing the heddle bars in the frames.

The primary object of the invention is to provide a securing means of this character which may be readily and easily operated to permit the heddle bars of a heddle frame to be readily and easily positioned or removed.

Another object of the invention is the provision of means for supporting the heddle bars in such a way as to hold the heddle bars steady at all times, eliminating vibration.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a fragmental elevational view disclosing the upper bar of the heddle frame, showing a heddle bar secured in position by a securing device, constructed in accordance with the invention.

Figure 2 is a vertical sectional view through the upper bar, and illustrating a securing device constructed in accordance with the invention, as mounted thereon, the securing device being in a position to receive a heddle bar.

Figure 3 is a vertical sectional view through a bar of the heddle frame, and illustrating the securing device in its active position.

Referring to the drawing in detail, the reference character 5 designates the upper bar of a heddle frame, which is held in proper spaced relation with the lower bar not shown, of a heddle frame, by means of the end piece 6.

The end piece 6 is of course duplicated on the opposite end of the heddle frame, and these end pieces are formed with openings to receive the conventional flexible heddle bars 7, that are disposed adjacent to the upper and lower ends of the heddle frame, and on which the heddles, which are indicated by the reference character 8, are held.

50 The securing device forming the subject matter of this invention, supports the heddle bars near the ends thereof, and comprises a body portion 9 formed with a threaded shank 10, by means of which the securing device may be secured to the bars of a heddle frame.

As clearly shown by Figure 2 of the drawing, one edge of the body portion 9 is cut away throughout a portion of its length, defining an inclined lower shoulder 11.

The cut away portion of the body portion, accommodates the heddle bar, the inclined shoulder 11, providing means to insure against the heddle bar becoming accidentally displaced.

The reference character 12 designates a lock plate, that is pivotally mounted on the body portion 9, at a point directly above the cut away portion thereof. One end of the plate is bifurcated, the space between the furcations being sufficiently wide to receive the heddle bar indicated at 7.

The lock plate 12 is formed with an opening which is slightly larger than the pivot pin 14, that connects the lock plate to the body portion, so that slight vertical movement of the plate 12 will be permitted.

One edge of the lock plate 12 is cut away at 15, providing a shoulder at one corner of the lock plate, while the upper edge of the lock plate is shown as straight, to engage the arm 16 of the spring 17, that is secured above the lock plate.

Thus it will be seen that due to this construction, the lock plate may be moved to a position as shown by Figure 2 of the drawing, whereupon the heddle bar 7 may be slid between the furcations of the lock plate, and the lock plate swung to a position as shown by Figure 1.

The spring arm 16 will exert a pressure on the lock plate with the result that vibrations directed to the heddle bar, will be absorbed by the spring arm 16 holding the bar steady.

It will further be seen that when the lock plate 12 is moved to a position as shown by Figure 2 it will be held in this position, until the force of the spring arm 16 is overcome, by an inward pressure directed to the lock plate.

Having thus described the invention what is claimed is:

1. A heddle frame comprising a heddle supporting bar, a heddle bar, a heddle bar securing device extending into the heddle supporting bar, and comprising a body portion having a cut out portion, a plate pivotally mounted on the body portion and having a bifurcated end defining a substantially long furcation and short furcation, said heddle bar adapted to be held between the furcations, and moved to a position within the cut out portion of the body portion, and said heddle bar adapted to be gripped

100

110

- between the short furcation of the plate, and rear edge or cut out portion.
2. A heddle frame comprising a heddle supporting bar, a heddle bar, a heddle bar securing device mounted on the heddle supporting bar, and comprising a body portion having a cut out portion, a plate pivotally mounted on the body portion, said plate having a bifurcated end providing an opening for the reception of the heddle bar, and means for restricting movement of the plate.
3. A heddle frame comprising a heddle supporting bar, a heddle bar securing device mounted on the heddle supporting bar, and including a pivoted member having a bifurcated end providing an opening to receive the heddle bar, and means for holding the pivoted member against accidental displacement.
4. A heddle frame, comprising a heddle supporting bar, a heddle bar, a heddle bar securing device mounted on the heddle supporting bar and comprising a stationary member and a pivoted member, said stationary member having a cut out portion providing a rest for the heddle, said pivoted member having a notch extending from the free end thereof, said notch being of a width to receive a heddle bar and said plate adapted to move the heddle bar into the cut out portion of the stationary member.
5. A heddle frame comprising a heddle supporting bar, a heddle bar securing device mounted on the heddle and comprising a stationary member having a cut out portion formed in one edge thereof, a pivoted member cooperating with the stationary member and having a cut out portion in one end thereof to receive a heddle bar, said plate adapted to move the heddle bar to a position within the cut out portion of the stationary member, and a spring member engaging the pivoted member, normally holding the pivoted member against movement.
6. A heddle frame comprising a heddle supporting bar, a heddle bar securing device comprising a stationary member having a cut out portion formed in the side edge thereof, a pivoted member mounted on the stationary member, said pivoted member having a cut out portion in the outer edge and extending from the free end thereof for the reception of a heddle bar, said pivoted member adapted to swing to a position in alignment with the cut out portion of the stationary member, securing the heddle bar within the frame, and means for normally holding the pivoted member against movement.
7. The combination with a heddle supporting bar, of a heddle bar securing device comprising a stationary member secured to the heddle supporting bar and having a cut out portion formed in one edge thereof, a pivoted member mounted on the stationary member adjacent to the cut out portion, said pivoted member having a cut out portion extending inwardly from the free end thereof and adapted to accommodate a heddle bar, said pivoted member adapted to move the heddle bar into the cut out portion of the stationary member, and means for normally holding the pivoted member against movement.
8. The combination with a heddle supporting bar, of a heddle bar securing device comprising a stationary member having an opening for the reception of the heddle bar, a pivoted member mounted on the stationary member and having an opening in the outer edge thereof at the free end of the pivoted member in which the heddle bar is positioned, and said pivoted member adapted to move inwardly with the heddle bar when the heddle bar is forced inwardly.
